UNITED STATES PATENT OFFICE.

CARL J. PRINZLER, OF INDIANAPOLIS, INDIANA.

DESIGN FOR A PANIC-LOCK.

48,651.

Specification for Design.

Patented Feb. 29, 1916.

Application filed August 14, 1914. Serial No. 856,871. Term of patent 7 years.

To all whom it may concern:

Be it known that I, CARL J. PRINZLER, a citizen of the United States, residing at Indianapolis, in the county of Marion, State of Indiana, have invented a new, original, and ornamental Design for Panic-Locks, shown in the accompanying drawing, which is a perspective view thereof looking toward the plane of a door upon which it is to be fastened.

I claim as my invention:

The ornamental design for a panic lock as shown.

CARL J. PRINZLER.

Witnesses:

FRANK A. FAHLE,
ARTHUR M. HOOD.
